[57] CLAIM

The ornamental design for a floral display saddle for a
grave marker, as shown and described.

DESCRIPTION

FIG. 1 is a side elevational view of a floral display
saddle for grave markers showing my new design, the
portion of a grave marker being shown in broken lines
of illustrative purposes only;

FIG. 2 is a left end elevational view thereof, again the
portion of a grave marker being shown in broken lines
for illustrative purposes only;

FIG. 3 is a right end elevational view thereof;

FIG. 4 is a side elevational view opposite that shown in
FIG. 1;

FIG. 5 is a top plan view thereof;

FIG. 6 is a bottom plan view thereof;

FIG. 7 is a side elevational view thereof, in a contracted
position;

FIG. 8 is a side elevational view thereof in an extended
position;

FIG. 9 is a side elevational view of half of the saddle,
the fasteners and other half being omitted for clarity of
illustration;

FIG. 10 is a left end elevational view of FIG. 9;

FIG. 11 is a right end elevational view of FIG. 9;

FIG. 12 is a side elevational view opposite that shown
in FIG. 9;

FIG. 13 is a top plan view of FIG. 9; and,

FIG. 14 is a bottom plan view of FIG. 9.
